Parsons & Bodell ATTORNEY.

UNITED STATES PATENT OFFICE.

DUNCAN M. JOHNSTON, OF CAMILLUS, NEW YORK, ASSIGNOR TO PASS & SEYMOUR INC.,
OF SOLVAY, NEW YORK, A CORPORATION OF NEW YORK.

ELECTRIC SWITCH UNIT.

Application filed March 1, 1922. Serial No. 540,198.

To all whom it may concern:

Be it known that I, DUNCAN M. JOHNSTON, a resident of Camillus, in the county of Onondaga and State of New York, have 5 invented a certain new and useful Electric Switch Unit, of which the following is a specification.

This invention has for its object a switch unit mountable between the base and the cap 10 or rosette of an electric fixture, which cap or rosette is also mountable on the base, whereby the current from the service wires connected to the terminals on the base to the branch wires connected to the terminals 15 on the rosette and hanging pendant from the rosette can be turned on and off without disturbing the pendant wires, which unit is particularly simple in construction, is readily interchangeable with the rosette 20 usually mounted on the base, and is readily attached to such rosette, and further which is highly efficient and durable in use.

The invention consists in the novel features and in the combinations and constructions hereinafter set forth and claimed.

In describing this invention, reference is had to the accompanying drawings in which like characters designate corresponding parts in all the views.

30 Figure 1 is an elevation, partly in section, of an electrical fixture embodying my invention.

Figure 2 is a plan or face view of the base.

35 Fig. 3 is a face view of the cap or rosette. Figures 4 and 5 are respectively opposite end views of the switch unit.

Figure 6 is a vertical sectional view on line 6—6, Fig. 4.

40 Figure 7 is a vertical sectional view on line 7—7, Fig. 4, parts being omitted.

Figure 8 is a detail view of one of the terminals of the base and contiguous parts, one of the terminals of the cap and its contiguous parts and one of the terminals of the insert or unit and connections, the parts being shown as separated.

45 As will be understood by those skilled in the art, branch circuits are led off from the main line wires by the use of what is termed a rosette, which is mounted upon a base having terminals to which the service wires are connected.

The cap or rosette also has wire termi-

nals for connection to the terminals on the base and also for connection to the wires of the branch circuit. The branch circuits usually supply current for pendant lights.

This invention has for its object a switch unit which is readily interchangeably 55 mountable on the base with the rosette and by which the rosette is interchangeably 60 mountable on the switch unit or on the base.

1 designates the base which may be of any suitable form, size and construction, it being usually formed of insulation, as porcelain, and having wire terminals 2, 3 thereon for connection to the service wires. The base is secured to a wall or other support 65 as an outlet box, in any suitable manner 70 as by screws extending through holes 4.

The wire terminals 2, 3 are here shown as secured by screws 5 extending through the base from the rear side thereof and threading into such terminals. The terminals are provided with suitable binding devices as screws 6.

7 is a cap or rosette having wire terminals or plates 8, 9 on its inner face, a central opening 10 for the outlet of the branch circuit wires, and wire terminals 11, 12 electrically connected to the terminals 8 and 9 respectively by suitable conductors or wires 13, 14.

The faces of the cap and rosette are suitably recessed to provide cavities for the various terminals so that the rosette can be set on the base with its margin engaging the margin of the base; or on the switch unit to be described similarly set on the base 75 and the rosette on the switch body.

The switch unit comprises a body 15 of insulation having an internal cavity 16 and end walls 17, 18 substantially closing the ends of the cavity, and switch mechanism 95 located in the cavity and including operating means extending transversely of the body to the outside thereof as a pull chain 19; switch contacts or terminals 20, 21 mounted on the inner faces of one of the walls 17, 18 as the wall 18, a terminal 22 on the outer face of the wall 18 and connected by a screw 23 to the terminal 21, and sets of wire terminals 24, 25, and 26, 27 mounted on the ends of the body for connection respectively, to the wire terminals 2, 3 on the base and the terminals 11, 12 on the rosette, and a movable switch

member 28 within the body for connecting and disconnecting the terminals 20, 21 of opposite polarity.

The switch terminal 20 is connected to 5 the terminal 24 on the opposite or upper end of the body by conductors 29, 30, 31, and the switch contact 21 is connected through the wall 18 to the terminal or plate 22 on the opposite or lower side of such 10 wall 18 by a screw 23.

The plate 22 is opposed to the terminal 27. This terminal 27 is merely a retainer for the terminal or hook on the cap and coacts with the plate 22 to interlock the 15 terminal on the cap in contact with the plate 22.

The switch mechanism may be of any suitable construction, and as here shown, the switch member 28 is movable about the 20 pin or spindle 34 centrally of the axis of the block or body 1, and mechanism for imparting a snap action to the switch.

The construction of the switch mechanism forms no part of this invention, but forms 25 the subject matter of the pending application of Harry J. Morey, Sr. No. 256,831, filed Oct. 4, 1918, and of patents as follows:—Harry J. Morey, No. 1,214,353, Jan. 30, 1917; Harry J. Morey, No. 1,284,420, 30 Nov. 12, 1918.

The switch unit is provided with means at the opposite ends of the body for mechanically connecting the body to the base and mechanically connecting the rosette to 25 the body and for electrically connecting the wire terminals 2, 3 on the base of the terminals 24, 25 on the opposite end of the switch block or body and electrically connecting the terminals 26, 27 on the outer 40 end of the switch body to the terminals 11, 12 on the opposing face of the rosette; and preferably, the mechanical means for connecting the switch unit to the base and to the rosette also electrically connect the conductors and terminals of the switch body 45 to the terminals of the base and rosette.

In the illustrated embodiment of my invention, this means operates to connect the switch body to the rosette and the base to 50 the switch body upon a relative partial turning movement of these parts, as for instance, the body is attached to the base by a relative turning movement thereof relatively to the base and the rosette is attached 55 to the switch body by a turning movement of the rosette.

As here illustrated, the wire terminals 2 and 3 on the base are formed with portions 34, 35 which overhang the bottom of the 60 recess in the base, and the opposing end of the switch body 15 is formed with hook-shaped extensions 36, 37 of the terminals 24, 25 respectively, which interlock under said overhanging portions 34, 35 by a partial 65 turning movement of the block.

Preferably, a spring clip 38 is interposed between each terminal 2, 3 of the base and the hook 36 or 37, these clips being usually secured to the terminals on the base, and tend to snugly hold the parts in engaged 70 relation and prevent any looseness or rattling and compensate for any inequalities in the engaging surfaces of the base and the switch block.

Likewise, in the illustrated form of my 75 invention, the terminals 11 and 12 on the rosette are provided with angular or hook-shaped portions 39, 40 arranged to interlock with overhanging portions 41, 42 of the terminals 26, 27 on the outer end of 80 the switch body 15, and a clip 48 similar to the former clip 38 is associated with the portion of the terminals 26, 27 overhanging a portion of a recess into which the hooks 85 extend. The clip 48 associated with the terminal 27 presses the hook-shaped terminal 39 or 40 against the terminal plate 22.

These hooks 39, 40 are also capable of 90 interlocking with the terminals 2, 3 on the base in the same manner as the hook extensions 36, 37 of the terminals 24, 25 interlock with the terminals 2, 3 so that the cap is interchangeably mountable either on the outer end of the switch block or on the 95 base.

Assuming that the terminal 2 of the base is engaged through its clip 38 with hook-shaped terminals 37 on the upper end of the switch body and that terminal 3 on the base is similarly engaged through its clip 38 with hook-shaped terminals 36 on the upper end of the switch body 15; and top plate 22 and terminal 27 are engaged through the clip 48 with the hook-shaped terminals 39 on the rosette and that terminal 26 on the lower end of the switch body 15 is engaged through its clip with the hook-shaped terminal 40 on the rosette or cap and that the switch is "on".

The current may flow as follows. terminal 2 to the base hook-shaped terminal 37 on the upper end of the switch body, conductor or screw 37^a Fig. 8, terminal 26 on lower end of switch body, clip 48 associated therewith, hook-shaped portion 40 of terminal 110 12 on the rosette through wire 13 to terminal 8 to which one leg of the branch circuit is connected, then through the branch circuit to terminal 9 on the rosette, through wire 14 to terminal 11 and hook 39 thereof on the rosette, and the companion clip 48. Thence, through plate 22, screw 23, switch terminal 21 through switch arm 28, terminal 20, screw 31, conductor 30, screw 115 or conductor 29 to terminal 24, and hook-shaped portion 36 thereof. Thence, through companion clip 38 overhanging end of terminal 3.

The flow of the current and the arrangement of the conductors form no part of this 120 125 130

invention, which relates to a switch unit insertable between the ordinary base and cap of an electric fixture and mechanically and electrically connected to the base and cap by relative rotary movements.

What I claim is:

The combination with a base having wire terminals thereon, a cap having branch wire terminals the terminals of the base and the cap being complementary to each other and constructed to interlock upon a partial rotary movement of the cap, to electrically engage said terminals, and to mechanically secure said cap to the base, of a switch unit having terminals at its opposite ends complementary respectively to the terminals of the base and the cap, and those at one end being arranged to interlock with the base terminals upon a partial rotary movement

of the unit, to electrically connect the terminals of the switch unit and the terminals of the base and mechanically secure the switch unit to the base, and the terminals at the other end of the switch unit being constructed to interlock with the terminals of the cap upon a partial relative turning movement to electrically connect the terminals of the unit and the cap, and mechanically secure the cap to the switch unit, whereby the cap is interchangeably mountable on the base and on the switch unit, and the unit is interchangeably mountable on the base with the cap.

In testimony whereof, I have hereunto signed my name, at Syracuse, in the county of Onondaga, and State of New York, this 21st day of February, 1922.

DUNCAN M. JOHNSTON.
